OIL WELL SURVEYING INSTRUMENT

Daniel B. Monroe, Denver, Colo., assignor of two-thirds to L. C. Terry and Fred M. Manning, both of Denver, Colo.

Application April 2, 1935, Serial No. 14,263

6 Claims. (Cl. 33—205.5)

This invention relates to a surveying instrument for oil wells, and has for its principal object the provision of a highly efficient device which can be lowered into a well casing or drill stem 5 to produce an accurate record of the vertical inclination of said well.

Another object of the invention is to provide an instrument of this character which will at any predetermined time interval make a record of both 10 the vertical degree and compass direction of the inclination of the well at any given point.

A further object is to provide a target perforating device in which the perforating needle will be withdrawn from the target after the perforating operation so that movement of the device will 15 not injure the needle or the perforation.

Other objects of the invention are to produce a device of this character which will be rigid in construction to withstand the usual oil well conditions; which will have but a minimum of parts; and which will be absolutely positive and accurate in operation.

Other objects and advantages reside in the detail construction of the invention, which is designed for simplicity, economy, and efficiency. 20 These will become more apparent from the following description.

In the following detailed description of the invention reference is had to the accompanying drawings which form a part hereof. Like numerals refer to like parts in all views of the drawings and throughout the description.

In the drawings:—

Fig. 1 is a side elevation of the complete device 35 with the barrel thereof cut in section to show the interior elements.

Fig. 2 is an enlarged vertical section through the operating portion of the device illustrating the latter in the "released" position.

Fig. 3 is a similar section through the compass portion of the device illustrating the latter in the "set" position.

Fig. 4 is an enlarged (full size) detail plan view of the indicating target, looking on the line 4—4, 40 Fig. 3.

Fig. 5 is a side elevation of the indicating target partially in section.

Fig. 6 is a fragmentary side view of the trigger portion of the invention.

Fig. 7 is an enlarged vertical detail section through the plumb bob employed in the invention.

Fig. 8 is a detail horizontal enlarged section through the plumb bob bearing.

Fig. 9 is a horizontal section through the inner 55 housing taken on the line 9—9, Fig. 3.

The invention comprises an outer barrel 10 preferably of brass or other suitable non-magnetic material. An extension tube 50 is threaded into the upper extremity of the barrel 10 and extends upwardly therefrom a sufficient distance to brace 5 and guide the barrel in alignment with the drill stem of the oil well into which the device is lowered. A guiding point 12 is threaded into the lower extremity of the barrel 10. A supporting plug 13 is secured in the top of the extension tube 10 50 and provided with suitable means for attaching it to a lowering wire 14. A guide shield 15 is positioned about the wire 14 and threaded onto the plug 13 to guide the device past obstructions while being raised in the drill stem. A partition 15 plate 52 is secured in the barrel 10 adjacent its upper extremity.

An inner housing 11 is slidably fitted into the barrel 10 and is supported therein between the partition plate 52 and the guide point 12 upon 20 suitable sponge rubber cushions 53. These cushions are sufficiently large and resilient to protect the contained mechanism from jars or shocks while being raised or lowered in the well.

A bearing block 16 is supported in the upper 25 portion of the inner housing 11 upon a suitable shoulder ring 51 and supports ball bearings 17 which in turn support a weighted plumb bob 18. The plumb bob 18 depends from a bearing ball 19 which rests on the ball bearings 17. The bearings 30 17 and the ball 19 are covered and protected by a suitable bearing cap 20.

The plumb bob 18 contains a needle 21 having an accurately ground point which projects from the bottom of the plumb bob. This point swings 35 immediately above an indicating target card 22 which is removably carried on the upper extremity of a combined compass sleeve and target support 23.

The compass sleeve 23 is vertically slidable 40 in the inner housing 11, and contains a compass case 24 in which a compass needle 25 is mounted upon a fixed pivot pin 26. The compass case is secured to the compass sleeve 23, and the entire assembly is supported in the inner housing 11 upon a link 27 which in turn is supported from a pivoted, spring actuated lever 28.

A spring 29 constantly tends to swing the lever 28 about its pivot from the position of Fig. 3 to that of Fig. 2. When the device is set, this movement is prevented by an L-shaped trigger 30 50 tripped by suitable clock 31. The clock 31 rotates a notched cam 32, upon which, the trigger 30 rides, as shown in Fig. 3. When the trigger 30 drops into the notch of the cam 32, its ex- 55

tremity releases the lever 28 allowing it to snap around almost a complete revolution until it strikes a stop spring 33.

In swinging, the lever 28 will move the link 5 27 first upwardly until it passes its uppermost point, thence downwardly to the stop position of Fig. 2. This up and down action of the link 27 pushes the entire compass housing upwardly so that the indicating target 22 will be forced 10 against the point of the needle 21 to perforate the target. It then lowers the target to again release the indicating point of the plumb bob.

The swinging lever 28 is fixed upon the extremity of a key shaft 44 which terminates in a setting key 45. The latter provides a convenient finger hold for rotating the lever 28 against the spring 29 to a position behind the trigger 30.

A compass locking arm 34 surrounds the pivot 26 below the compass needle 25. The locking arm 34 is carried from a push pin 35 and acts to force the compass needle from its pivot against an upper stop member 36. The push pin 35 is operated from a lever 37 pivoted on a bracket extending downward from the compass case 24. 25 A stop pin 38 extends across the housing 11 in the path of the lever 37 so that as the compass case moves upwardly to perforate the target 22, the extremity of the lever 37 will strike the pin 38, causing the former to push the push pin 35 upwardly. This lifts the locking arm against the compass needle and clamps the latter tightly against the stop member 36. The push pin 35 is held in either the elevated position of Fig. 30 or the lowered position of Fig. 3 by means of 2 or the lowered position of Fig. 3 by means of 35 a rocking compression spring 39. The spring 39 presses against the side of the pin 35 and creates sufficient friction to prevent the latter from dropping the compass needle when the compass case 24 returns to its lowermost position. It has been 40 found that the holding action of the spring 39 is increased if the extremity thereof which contacts the pin 35 is allowed space for vertical movement. Then when the pin is up and locking the compass needle, as shown in Fig. 2, the spring will be 45 pushing upwardly and, when the pin is down, as shown in Fig. 3, the spring is acting downwardly. The stop member 36 may be supported in a glass cover plate 55 over the compass.

It will be noted that the compass case 24 is 50 relatively deep and that its glass cover 55 is spaced quite high above the compass needle. This allows vertical latitude for the needle to accommodate inclinations of the instrument when in use.

55 It is desired to call particular attention to the construction of the plumb bob 18, and its supporting bearing. The bob consists of a central tube 40 about which is secured the weighted plumb bob proper 18. The latter is conical in 60 shape with its smaller extremity downward. The lower extremity of the tube 40 projects from the bob and is also tapered to a relatively pointed extremity. The upper extremity of the tube 40 projects above the bob and is threaded to be 65 received in a threaded socket 41, upon an extension of which, the bearing ball 19 is formed. The needle 21 extends entirely through the length of the tube 40, and contacts at its upper extremity with the bottom of the inverted socket 41. A spring 42 constantly forces the needle upwardly. When the device is not in use, the tube 40 can be threaded downwardly in the socket 41 so as to bring its lower extremity over the needle point to protect the latter. When being set for use,

the tube 40 is threaded into the socket 41 to allow the needle point to project the desired distance.

It has been found that a more accurate swing of the plumb bob results if the ball bearings 17 5 are separated by means of smaller balls 43, as shown in Fig. 8. Only the large balls contact with the bearing ball 19.

The indicating target consists of a cardboard disc marked in degrees of compass direction 10 around its periphery and marked in degrees of inclination by a series of concentric numbered circles as shown in Fig. 4. The cards are held upon a diaphragm surface 46 and are clamped in place thereon by means of a clamping ring 15 47. The upper surface of the clamping ring 47 is marked with degree marks as indicated by the lines and dots in Fig. 4. The upper edge of the compass sleeve 23 contains an index arrow 48 and the edge of the clamping ring 47 carries 20 a registering arrow 49. The inner housing wall is cut away or "skeletonized" opposite the target and clock as shown in Fig. 1 to allow ready visibility and access to these parts of the device. 25

Operation

Let us assume that it is desired to check the drill stem of a rotary rig to ascertain if it is deviating from vertical. The operator unscrews the guide point 12 and slides the inner housing from the barrel 10. He then removes the clamping ring 47 and places a target disc 22 therein, positioning the target so that the "north" point thereof will come opposite the indicating arrow 49. He then replaces the ring 47 with the target 25 on the upper extremity of the compass sleeve 23, with the arrow 49 opposite the arrow 48. This procedure insures the "north" point of the target being accurately positioned over the "north" point of the compass case 24. By means 40 of the key 45, he sets the lever 28 behind the trigger 30 and sets the clock so that it will bring the notch of the cam 32 beneath the trigger 30 after a sufficient time interval has elapsed to allow him to lower the instrument to the desired depth. 45

The various parts are then reassembled in the barrel 10 and the latter is lowered into the drill stem usually on the measuring line of the rig, to the drilling extremity thereof. The device 50 is left at rest until the pre-set time interval has elapsed, to allow the plumb bob to come to rest. At the expiration of this time interval, the notch in the cam 32 will release the trigger 30, allowing the lever 28 to swing so as to lift 55 the target against the needle point to perforate the former and so as to lift the compass locking sleeve 34 to lock the compass needle 25.

The device is now withdrawn from the well, and the inner housing is removed from the barrel 10. The operator notes the perforation made in the target 22 by the needle point and can instantly determine by means of the concentric circles the exact degree of inclination from vertical, if any. He can also read by means of the 60 compass index on the target the exact direction of the inclination.

Devices have been tried in which a plumb bob needle perforates a target. In some of these, the needle remained in the perforation after the 70 perforating operation. During the side sway and shock caused by drawing the instrument from the well the target would often be so badly damaged as to render an accurate reading impossible. If the target was of a material to 75

resist damage then the needle would be damaged. If the needle were made sufficiently heavy to resist this damage it could not perforate a small accurate perforation. This device avoids 5 all of this by instantly withdrawing the needle after the perforating operation.

It is preferred to place an annular rubber cushion about the upper edge of the compass locking sleeve 34 and on the lower extremity of 10 the locking member 36 to avoid damage to the compass needle and to assist in holding the latter firmly locked in place.

It is preferred to mount the cam 32 on the "hour" sleeve of the clock 31 and to secure an 15 index pointer 57 on the minute shaft thereof. The operator can then set the pointer 57 back any desired fraction of a rotation to obtain the desired time interval.

While a specific form of the improvement has 20 been described and illustrated herein, it is desired to be understood that the same may be varied, within the scope of the appended claims, without departing from the spirit of the invention.

Having thus described the invention, what is 25 claimed and desired secured by Letters Patent is:—

1. In an oilwell surveying instrument of the 30 class described, the combination of a laterally extending shaft; a slideable target support; a lever secured to and projecting from said shaft; a connecting rod connecting said lever with said target support; means for rotating said shaft to cause said connecting rod to axially reciprocate 35 said target support to and from a marking position; and means for releasing said lever at a predetermined time.

2. In an oilwell surveying instrument of the 40 class described, the combination of a laterally extending shaft; a slideable target support; a lever secured to and projecting from said shaft; a connecting rod connecting said lever with said target support; means for rotating said shaft to cause said connecting rod to axially reciprocate 45 said target support to and from a marking position; a trigger member in the path of said lever preventing operation of said means; and a clock-actuated device for releasing said trigger at a predetermined time.

3. In an oilwell surveying instrument of the 50 class described, the combination of a laterally extending shaft; a slideable target support; a lever secured to and projecting from said shaft; a connecting rod connecting said lever with said target support; means for rotating said shaft to cause said connecting rod to axially reciprocate 55

said target support to and from a marking position; a clock-actuated cam; a trigger member resting on said cam and projecting into the path of said lever, said cam being provided with a notch for releasing said trigger so as to allow 5 said means to reciprocate said target support; and means for stopping the rotation of said lever after a complete reciprocation of said target support.

4. In an oilwell surveying instrument of the 10 type described, the combination of a cylindrical, piston-like target support slideable within said instrument; a removable target on the top of 15 said target support; a laterally extending shaft below said target support; a crank lever secured on said shaft; a connecting rod extending from an eccentric position on said crank lever to said target support, so that rotation of said shaft will reciprocate said target support in said instrument to bring said target to a marking position and thence withdraw it therefrom; a spring urging said shaft to rotate in one direction; a trigger for withholding said shaft from rotation; a stop member preventing more than a 20 single rotation of said shaft; and means for releasing said trigger after a pre-set time interval.

5. In an oil well surveying instrument of the 25 class described, the combination of a slideable target support; a rotatable shaft positioned laterally to the line of movement of said target 30 support; a connecting rod eccentrically mounted with respect to said shaft and extending to said support so that the initial rotative movement of said shaft will force said support to a marking position and the remaining rotation thereof will 35 withdraw said support; a spring tending to rotate said shaft; a lever fixed to said shaft; a trigger holding said lever against the action of said spring; a clock; a cam actuated by said clock and supporting said trigger in the path of 40 said lever, said cam being notched so that at a predetermined time it will allow said trigger to move from the path of said lever to allow said shaft to make a revolution.

6. In a device of the class described, the 45 combination of, a rotary member; a slidably mounted target support; a spring for rotating said rotary member; a connecting rod eccentrically mounted with respect to said rotary member and extending to said target support; and means for releasing said rotary member at a predetermined time to allow the latter to make a partial revolution so as to force said target support toward a 50 marking position and withdraw it therefrom.

DANIEL B. MONROE.
